DESIGN FOR A GLOVE

Mabel Whitesell Balboa, Woodside, N. Y.

Application May 21, 1942, Serial No. 106,973

Term of patent 14 years

To all whom it may concern:

Be it known that I, Mabel Whitesell Balboa, a citizen of the United States of America, residing at Woodside, in the county of Queens, State of New York, have invented a new, original, and ornamental Design for Gloves, of which the following is a specification, reference being made to the accompanying drawing, forming a part thereof.

Fig. 1 is a front view, in perspective, of a glove showing my design with the cuff unfolded, and

Fig. 2 is a front view, in perspective, of the glove shown in Fig. 1 with the cuff folded back.

The back of the glove is conventional.

I claim:

The ornamental design for a glove, substantially as shown and described.

MABEL WHITESELL BALBOA.
